UNITED STATES PATENT OFFICE.

ERIC CARLSON, OF CHICAGO, ILLINOIS, ASSIGNOR TO STEWART MANUFACTURING CORPORATION, OF CHICAGO, ILLINOIS, A CORPORATION OF DELAWARE.

DIE-CASTING MACHINE.

Application filed September 11, 1922, Serial No. 587,264. Renewed December 7, 1925.

To all whom it may concern:

Be it known that I, ERIC CARLSON, a citizen of the United States, residing in the city of Chicago, in the county of Cook and the State of Illinois, have invented certain new and useful Improvements in Die-Casting Machines, of which the following is a specification, reference being had to the accompanying drawings, forming a part

10 thereof.

The purpose of this invention is to provide an improved construction of a die casting machine particularly designed to be better adapted for relatively large and heavy castings than machines of this class heretofore commonly employed, and adapted for as rapid operation as the size of the castings and the time necessarily required for their cooling in the mold will permit; and also adapted to be operated by a single operator controlling all the movements of the machine which are not entirely automatic. It consists in the elements and features of construction shown and described 25 as indicated in the claims.

In the drawings:

Figure 1 is a front side elevation of a machine embodying this invention, the parts being in the position occupied when the die 30 is open and the machine at rest, certain parts being broken away as shown in dotted line for disclosing operating parts otherwise incompletely visible.

Figure 2 is a top plan view of the same with the parts in the same position as Figure 1, certain parts broken away shown in dotted line for disclosing parts underneath them.

Figure 3 is a vertical section at the line 40 3-3 on Figures 2 and 4, but with the parts in the position occupied when the die is closed for casting.

Figure 4 is a left hand end elevation of the machine with certain parts removed to disclose others which are required to be seen in order to understand the movements.

Figure 5 is a partly sectional plan view, sections being made at the line 5-5 on Figure 4, axial with respect to the power shaft and at 5^a-5^a on Figure 1, the metal pots and supports and operating connections being removed.

Figure 6 is a detail section at the line 6-6 on Figure 1.

Figure 7 is a section at the line 7-7 on 55 Figure 4.

Figure 8 is a top plan view of the die-carrier frame and moving parts thereon without the fluid pressure cylinders and their supports.

Figure 9 is a side elevation of said frame including the cylinder supports stripped of mechanism.

Figure 10 is a section at the line 10-10 on Figure 5.

Figure 11 is a section at the line 11-11 on Figure 4.

Figure 12 is a detail plan view of the lever-locking device.

Figure 13 is a detail section at the line 70 13-13 on Figure 1 on an enlarged scale.

Figure 14 is a section at the line 14-14 on Figure 13.

In the machine shown in the drawings the metal pot is fixed and the die is advanced 75 and withdrawn for receiving the metal and discharging the casting. The pot is elevated and discharges downwardly into the die. The latter with all its parts and cores and operating connections is mounted for 80 moving horizontally by positioning the die under the pot, to be then uplifted to register its inlet with the pot discharge nipple.

The two parts of the die are moved relatively for opening and closing in the same 85 direction in which the die as a whole and all its parts and operating connections move for entering under and withdrawing from under the pot; and the closing and opening of the die occurs in the said entering and withdrawing movement, by virtue of different speed of movement of the two die members; that is, the two die members being positioned one behind the other in the path of advance for entering under the pot, the rear or follower member moves more rapidly than the leading member and overtakes the latter about the time the registering position is reached and the die is ready to be uplifted in order to register with the 100 pot nipple.

The cores and the immediate mechanical connections for operating them are mounted on the follower member of the die which,

rather than the other, may be regarded as the main die member. The cores are thrust in and withdrawn by fluid pressure, separate cylinders and pistons being connected with the core or cores respectively entering the die from opposite sides. The fluid pressure for operating the cores by means of the cylinders and the pistons is manually controlled, the operator opening the valve which admits pressure fluid to the cylinder before starting the machine for the other movements and operations.

The discharge of the metal from the die is controlled by a valve at the discharge nipple; and said discharge is forced by fluid pressure admitting to the pot above the metal therein, the pot being tightly closed except as to the fluid pressure admission and metal discharge port. The valve which controls the admission of fluid pressure to the pot is operated by another cam on said shaft so that the time relation of the opening of the metal discharge valve and the admission of pressure for causing discharge is predetermined absolutely and as desired by the adjustment of the cams on the shaft. The power shaft has cams which operate the connections for giving the two die members their movements respectively for closing in advancing under the pot and opening or withdrawing from under the pot; and it has also other cams for lifting the die structure bodily to register the die inlet with the pot discharge nipple at the limit of the closing and advancing movement of the die.

The adjustment of the several cams on the shaft provides for proper relative timing of the several operations to cause them to occur in the following order:—

The operator having opened the manual valve for admitting fluid pressure to the cylinders for operating the cores, operates the control lever for supporting the machine. The rotation of the power shaft then causes it to perform the several functions in the following order:—

First:—The die moving cam starts both the die members moving toward the pot, the follower moving more rapidly than the leader and overtaking the latter when the metal inlet of the die, which is in the leader, is in position directly under the pot nipple.

Second:—The lifting cam lifts the die bodily to register its inlet with the pot nipple and holds it snugly thereagainst.

Third:—The pot-valve-operating cam opens the discharge valve of the pot; and next at a very brief interval or simultaneously, the fluid-pressure controlling cam which controls admission of pressure to the pot for discharge of the metal to the die, opens the pressure controlling valve and almost immediately passes the dwell of the

cam and closing said valve opens the exhaust port relieving the pressure of the pot.

Fourth:—The pressure being off the pot, the pot-valve-operating cam passes the dwell and a spring in the operating connections of said valve causes it to be opened.

Fifth:—The die-lifting cam has at this time, passed its dwell, and is in its return course causing the die to be lowered away from the pot.

Sixth:—The cams which operate the die connections for moving the die members toward and from the pot and for opening and closing have now passed their dwell for holding the die in registration with the pot, the continued rotation of the power shaft causes them to retract both die members, the follower more rapidly than leader, thereby opening the die by the time the parts have reached initial position; and the cast is now removed by suitable manual means.

The machine shown in the drawings for operating as above described comprises a supporting structure consisting of a base having end standards, 1 and 2, and connecting side bars, 3, 3, and a bed member, 4, mounted upon said base. Upon the bed member at the rear end the metal furnace and metal pot are mounted being upheld by uprights, 5, 5, projecting rigidly up from the bed and carrying at their upper end the furnace or heater, 6, in which the metal pot, 7, is suspended, being supported by a marginal flange, 7^a, at the top of said pot engaging the margin of the aperture, 6^a, in the top web of the heater. 8 is a gas conduit extending in annular form around the top of the heater having a connection at 8^a, with the gas supply pipe and having, leading downward from the under side and inward through the heater wall, gas burner connections, 8^b, 8^b. The metal pot has a discharge nipple, 7^b, at the bottom controlled by the valve, 9, whose stem extends out through a suitable stuffing box, 10, mounted on the top web of the pot, and is connected for operation by a lever, 11, fulcrumed on a bracket, 7^c, which projects upwardly from the top of the pot. The lever is operated by a downwardly extending pull rod or connecting link, 11^a, which comprises an adjusting turn buckle, 11^b, and extends through a guide lug, 4^a, which projects from the bed, 4, and is provided above said lug with a spring, 11^c, coiled around the rod and reacting at its upper end against a tension-adjusting nut, 11^d, whereby the spring reacts for thrusting the link upward and thereby thrusting down the valve-carrying end of the lever, 11, for closing the valve when relieved from the action of the valve operating cam hereinafter described.

12 is a fluid pressure pipe. This pipe leads from the fluid pressure controlling valve, 13,

hereinafter described with its operating connections.

The die carrying structure, B,—so indicated as a whole,—is mounted on the bed, 4, at the forward end portion thereof. It comprises a carrier, C, for the leader-die holder. This carrier comprises a base, 16, having wheels or rollers, 17 and 18, for riding respectively upon tracks, 4^b and 4^c, mounted upon the top of the bed, 4. The track, 4^c, as shown comprises both an upper and lower track member so that the rollers, 4^d, are checked against uptilting of the carrier as well as supported on the bed. This carrier comprises also standards, 19 and 20, at the end respectively toward and remote from the pot, and an intermediate standard, 20^x, and upper and lower longitudinally extending parallel frame rods, 21, 21, and 22, 22, which serve also as guide bearings for the carrier of the support for the follower die member. Upon the standards, 19 and 20^x, there are erected the supporting frames, 36, 36, for the fluid pressure cylinders, 37, 37, for operating the core carriers as hereinafter fully described. Upon the guide rods, 21 and 22, there is mounted for moving longitudinally thereof, said carrier for the holder of the follower die member. The holder for the follower die is seen at 23. The carrier comprises a traveler, 24, mounted for sliding on the rods, 21 and 22, and having projecting horizontally from its opposite sides downwardly facing racks, 25, 25, and journal bearings, 24^a, 24^a for horizontally extending rock shafts, 26, 26, which are journaled also in bearings, 29, 29^a, on the standards, 20 and 21, respectively, of the carrier, C. On the rock shaft, 26, extending between the standards, 19 and 20^x, there are sleeves, 30, 30, having each a longitudinal slot, 31, into which a stud-and-roll, 32, projects from the shaft, 26, for driving engagement of the shaft by the sleeve to rock the shaft in the rocking of the sleeve which is caused by the fact that said sleeve is in effect the wrist or hub of a terminal, 33^a, which is secured to a radial lever arm, 33, of the sleeve at one end of the latter, said lever, 33, being pivotally connected at the other end to the outer end of the stem, 34, of the piston, 35, playing in the cylinder, 37, mounted pivotally in the standards, 36, as above described. The above description it will be understood applies to the similar and substantially identical connections from the two cylinders, 37, to the two rock shafts, 26, respectively.

The rock shafts, 26, have at their end toward the leader-die-holder segment gears, 27, meshing with the racks, 25, respectively, for reciprocating the core carriers to thrust the cores into and withdraw them from the follower die member carried on the holder, 23.

The movements described and indicated in the foregoing general description of op-

eration are derived from the power shaft, 57, journaled in bearings, 2^a, 2^a, provided upon the outer or forward end of the front standard, 2, a third bearing being provided at 2 in the bracket, 58, which is mounted by means of a base flange, 58^a, on the rear side of the standard, 2, for the co-axial driving shaft, 57^x, which communicates reduced speed to the shaft, 57, through the planetary gear system shown at D and hereinafter described. Power is communicated by means of a band wheel, 59, loose on the shaft, 58, having adjacent thereto between said band wheel and the bearings, 2^b, a clutch wheel, 60, keyed fast to the shaft. The power wheel is engaged with the clutch wheel, and thereby with the shaft by means of the clutch dog, 61^b, pivoted at 59^a on the clutch wheel comprising at the inner end of its journal a short clutch head, 61^b, which is adapted to make a cramping engagement with the inner surface of the annular flange, 59^b, on the power wheel, 59, the outer end of the dog having a lever arm, 61^a, which projects in obliquely,—that is non-radially with respect to the wheel and shaft,—in position to be encountered and deflected for rocking the dog into cramping position by the cone-tapered end of a shipping collar, 62, mounted for sliding on the shaft and having a peripheral groove, 62^a, engaged by the fork, 63^a, of the shipping arm, 63, which is carried on a shaft, 64, mounted in lugs, 58^b and 58^c, on the bracket, 58. A spring, 65, coiled around the shaft, 64, stopped at one end against the bearing lug, 58^b, and at the other reacting against the hub of the shipping arm, 63, holds the shipping collar, 62, out of engagement with the dog, leaving the shaft disengaged from the power wheel. For operating the clutching means described to cause the shaft to be driven, there is provided a bell crank, 77, fulcrumed on the under side of the bed, 4, having one arm forked and engaged between two collars, 66, 66, on the shaft, 64, the other arm being connected by a connecting rod, 78, with a hand lever, 79, fulcrumed on a bracket, 1^b, mounted on the outer side of the standard, 1, and extending up at the forward end of said standard terminating in a handle, 79^a, for manual operation. 80 is a locking device pivoted on the bed and having a catch hook, 80^a, for engaging the lever, 79, and provided with a spring, 81, for tending to swing and hold it in locking position; so that the operator swinging the lever, 79, into position when the operator swings the lever, 79, into position for throwing on the power, immediately upon the starting of the movements which comprise the withdrawal of the carrier base, 16, away from raised position seen in Figure 5, to the position seen in Figure 12, the lever is locked and remains held in that position until released by the disengagement of the

lock, such release occurring automatically upon completion of the cycle of the movements of the machine which comprise one complete revolution of the power shaft and 5 the return of the carrier base to raised position, as in Figure 5. For disengagement of the lever, 79, thus automatically upon the completion of the cycle, there is provided a projection, b^2 , from the base, 16, of the die 10 carrier, B, which encounters a lug, 80, on a lock, 80, at the limit of the die-retracting movement of said carrier, which is the concluding movement of the cycle, and by such encounter disengages the lock from the 15 lever, 78, which thereupon permits the spring, 65 to disengage the clutch leaving all parts of the machine at rest in normal initial position.

The planetary gear speed reducing system, D, consists of three epicyclic gear pinions, each double, that is composed of two gears, 100 and 100^a, carried on a rotor, 101, having a sleeve hub, 102, by which it is mounted fast on the shaft, 57^x, the power 20 wheel, 59, being journaled loose on said sleeve hub. The epicyclic pinions have their smaller gear, 100, meshing with an internal gear, 103, which is fixed being secured at its periphery to the periphery of a casing, 104, 25 for the planetary system, said casing being mounted fast in the standard, 2. The larger gear member of the epicyclic pinions, 100^a, meshes with a second internal gear or sun wheel, 105. The ratio of the number of 30 teeth of the gear, 105, to the number of teeth of the pinion, 100^a, is less than the ratio of the number of teeth of the internal gear, 103, to the number of the teeth of the pinion, 100. As designed in the present machine, 35 the internal gears, 100 and 101, differ in the number of their teeth by one (1), and the epicyclic pinions have each the same number of teeth; so that the internal gear, 101, makes one revolution for as many revolutions of 40 the rotor as the number of teeth in the fixed gear, 100, which is about fifty.

On the power shaft, 57, there are cams for controlling,—and in respect to certain of them, producing,—the movements indicated 50 in the foregoing description of operation of the machine. The cam, 40, on said shaft, 57, actuates a lever, 41, pivoted at 2^d, on the standard, 2, and carrying in its opposite forked end a nut, 41^a, through which the lower end of the link, 11^a, is screwed for adjusting the length of said link to permit the valve, 9, at the discharge port of the metal pot to be properly seated when the lever, 41, is free from the action of the cam, and to 55 properly open said valve, 9, when the crest of the cam is operating against said lever. At the end of the shaft, 57, remote from the power wheel it carries a cam, 42, which in 60 the rotation of the shaft actuates a lever, 43, for opening the valve, 44, which controls

admission of pressure fluid to the pot for discharging the metal therefrom. The dwell of the cam, 42, is short as may be seen from Figure 7, and immediately upon passing the dwell the action of the cam is to shift the 70 valve, 44, to position for opening the exhaust, 44^a, at the same time closing the inlet port, 44^b, and relieving the metal in the pot from pressure fluid.

45, 45, are reciprocally formed face cams 75 mounted on the shaft, 57, with their faces having the cam grooves, 45^a, toward each other. 46 is a duplex link or thrust bar which is forked as seen at 47 for striding the shaft, 57, said thrust bar having at the 80 head of the fork stud-and-roll abutments, 48, 48, projecting oppositely for engaging the grooves of the two cams, 45, 45. The other end of the thrust bar is pivotally connected to a rocker, 49, fulcrumed on a bracket, 4^d, depending from the bed, 4. The rotation of the shaft causes the cams, 45, to reciprocate the thrust bar, 46, with a dwell at the limit of the pulling stroke,—at the 85 position shown in Figure 3. The rocker, 49, is connected for giving the reciprocating movement described to the two parts of the die, referred to respectively as the "leader" and "follower". For this purpose said rocker has two link connections, one by the 90 link, 51, connected to the upper forward corner of the rocker and extending forward,—that is in the direction of movement of the die for registering with the pot,—and connected to a lug, 16^c, projecting from the 95 base, 16, of the carrier for the leader die member. From the other,—lower rear corner of the rocker,—it is connected by a thrust link, 52, to a linkage system which 100 connects the carrier for the leader die with the carrier for the follower die. This linkage is duplex, that is, comprises duplicate members respectively parallel operating in 105 parallel planes at opposite sides of a longitudinal vertical medial plane of the carrier 110 as may be seen in Figure 9: Describing this linkage by reference to one set of said links only, it being understood that the 115 description applies equally to the other set, it consists of the bell crank lever, 53, whose lower end is connected to the upper end of the thrust link, 52, a radius link, 54, connected at one end to a pivot fixed with respect to the carrier for the leader die, 120 and at the other end to the bell crank lever at its angle. The first mentioned pivotal connection of said radius link is obtained on a longitudinal member, 90, which is mounted in the rear standard, 20, of the 125 carrier and extends at the mid vertical longitudinal plane of the carrier through the standard, 20^x. The bell crank lever, is pivoted midway between its angle, and the end remote from the connection with the 130 thrust link, 52, to a sleeve, 55, which is

mounted for sliding on the member, 90; and the end of the bell crank lever is pivotally connected to one end of the thrust link, 56, whose other end is pivotally connected to the carrier for the follower die.

- The operation of this linkage upon consideration will be seen to be, that the rocking of the rocker, 49, primarily operating to advance the carrier, B, by the thrust of 10 the link, 51, thereby carries the fulcrum of the radius link, 54, forward while the link, 52, is being thrust up by the rocker, with a tendency to rock the bell crank lever, 53, over its fulcrum connection with the radius link while that fulcrum is being advanced, with the result that the linkage consisting of the final thrust link, 56, and the upper or actuating limb of the bell crank lever which is folded at the initial position is 15 straightened out at the final position thereby increasing the distance between the fulcrum of the radius link which is fixed on the carrier, B, and the final pivotal connection of the thrust link, 56, on the carrier, 24. 20 The operation of thus straightening and thereby lengthening of the linkage is to advance the follower die into engagement with the leader die during the movement of the entire die and operating parts bodily, to 25 a position for registering the die with the pot nipple. The dwell of the cams, 45, occurs at the stage at which the follower die has overtaken the leader die and the latter has its inlet immediately under the 30 pot nipple. While the parts stand in this relative position the die is uplifted to register the inlet snugly with the pot nipple. This movement is produced by the cams, 120, on the shaft, 57, said cams having each 35 the slight upraises, 120^a, which at this stage encounter the vertical arms of the bell-crank levers, 121, fulcrumed at 122 on the standard, 2, and having their horizontal arms connected with the lower ends of the thrust rods 40 or die lifters, 123, guided in lugs, 124, on the bed, their heads being overhung at this stage by the die which has been thrust in above them in the die movements above described. In the up-thrust of the die lifters 45 the die carrier pivots over the wheels, 18, at its right hand end for the very short uplift of the die carrier and over the wheels, 17 at its left hand end which is necessary to bring its inlet into snug registration 50 with the pot nipple. Springs, 126, reacting between the lugs, 124, and the ends of the horizontal arms of the bell-crank levers, 121, retract the die lifters when the dwell of the cams, 120, is passed. The dwell of said cams 55 is coincident with the latter part of the dwell of the cams, 45, and during the overlap of their dwell the die is filled with the metal from the pot; whereupon, due to the relative position of the several cams on the shaft, 57, the pot-discharge-valve is closed 60

and the fluid pressure is cut off therefrom, these operations being followed by the retraction of the two die parts and their respective carriers in the reverse order of the movements above described for the advance 70 and closing of the die, while the thrust bar, 58, is retracted to initial position and the parts come to rest with the die opened and the cast accessible for removal.

The member, 90, is utilized or may be said 75 to be primarily, provided, for the purpose of a fluid-pressure-operated "knockout", said member being tubular and connected at the outer end with a pipe, 91, leading from a source of compressed air, a rod, 92, operating as a piston in the tubular member, 90, being actuated by the admission and exhaust of compressed air for tapping the die to loosen the casting, according to well understood practice; for which reason the connections and mechanism for causing the tapping action are not shown.

It may be understood that means are provided for cooling water circulation through the die holders as indicated by several hose 90 connections seen at 110. These are not different from common constructions and require no further showing or description.

I claim:—

1. In a die casting machine in combination with a supporting structure and a metal pot carried in fixed position thereon, a guideway on said structure for support and movement of the die to and from position for registering with the metal pot, a carrier mounted for movement along said guideway; holders for two die members to be closed together for receiving the metal and separated for removing the casting, said holders being mounted for movement tandem,—one leading and the other following,—from open to closed position of the die, the leader being mounted on said carrier, said carrier extending from a point in front of to behind the follower; linkage connecting the follower with a rear point on the carrier, said linkage adapted to be collapsed or folded by the retraction of the follower from the leader, and to project the follower toward the leader when straightened; a rocker having a fulcrum fixed with respect to the metal pot; link connections from said rocker to the carrier for reciprocating it along the guideway and a thrust link from the rocker to the linkage between the follower and the leader carrier, for straightening said linkage in the rocking movement which advances the carrier and folding the linkage in the opposite rocking movement.

2. In the construction defined in claim 1 foregoing, the chord of the arc of movement of the pivotal connection to the rocker of the link which reciprocates the carrier being approximately parallel to the path of re- 130

ciprocation of the carrier; whereby the link thrusts and pulls nearly horizontally and the path of movement of the pivotal connection of the rocker to the link which operates the follower die holder being in general upward and the thrust link extending upward for connection with the linkage to be straightened.

3. In the construction defined in claim 1 foregoing, the linkage comprising two parallel systems of links and levers of which the corresponding parts are respectively equal and parallel.

4. In the construction defined in claim 1 foregoing, the linkage comprising a bell crank member pivoted at its angle to one end of a link whose other end is pivoted on the carrier, said bell crank member being pivoted midway in the length of its actuating arm at a pivot mounted for sliding along the carrier and the extremity of said arm being pivoted to one end of a link whose other end is pivoted to the holder of the follower-die member.

5. In the construction defined in claim 1 foregoing, the linkage comprising a bell crank lever operatively connected at one end to the thrust link from the rocker, a radius link from the angle of the bell crank to a fixed pivot on the carrier; a pivot mounted for sliding along the carrier, the second or actuating arm of the bell crank being pivoted at its middle point to said sliding pivot and a thrust link from the extremity of the bell crank lever to the holder for the follower die.

6. In a die casting machine in combination with a frame structure comprising a substantially horizontal bed, a downwardly discharging metal pot mounted at elevated position thereon overhanging the bed, a die carrier mounted for movement longitudinally of the bed from a position clear of the pot to a position under the same; means for operating the carrier to so move the

die; means for elevating and upholding the die for registration of the die inlet with the pot discharge nipple; means for shutting off and for forcing discharge of the metal from the pot; a power shaft and cams thereon for operating in predetermined time relation the die-advancing and uplifting movements and the metal shut-off and the metal discharge means.

7. In the construction defined in claim 6, foregoing, the die carrier comprising holders for two die members adapted to be closed together for receiving the metal and separated for delivering the cast and means for relatively moving said holders to open and close the die, said means being connected for operation by the means for moving the die into and out of position for registration with the pot.

8. In the construction defined in claim 6, foregoing, the die carrier comprising core-carrying members, fluid pressure means for operating the core-carrying members, said fluid pressure means comprising a piston and cylinder carried by the die-carrying structure in the movement toward and from the pot and manually operable valve means on the supporting structure for controlling access of the fluid pressure to said cylinder.

9. In the construction defined in claim 6, foregoing, the means for forcing the discharge of metal from the pot to the die being fluid pressure means, a valve mounted on the supporting structure for controlling the access and exhaust of fluid pressure to the pot, the cam on the power shaft for operating said valve being formed and positioned for admitting and cutting off the fluid pressure coincidently with the opening and closing of the metal discharge valve.

In testimony whereof, I have hereunto set my hand at Chicago, Illinois this 7th day of September, 1922.

ERIC CARLSON.
